COMBINED TRASH RECEPTACLE AND
HOLDER THEREFORLoryn B. Deane and Edward V. Deane, both of 18 Overlook Road, Ardsley, N.Y. 10502

Filed Mar. 24, 1972, Ser. No. 238,007

Term of patent 14 years

Int. Cl. D7—06

U.S. Cl. D49—32

FIG. 1 is a top plan view of combined trash receptacle and holder showing our new design;

FIG. 2 is a front elevational view;

FIG. 3 is a rear elevational view; and

FIG. 4 is a side elevational view of the trash receptacle of FIG. 1.

We claim:

The ornamental design for a combined trash receptacle and holder therefor, as shown.
